COLLAPSIBLE TRAY

Robert B. Karoff, New York, N. Y., assignor to Karoff Originals, Ltd., New York, N. Y., a corporation of New York

Application November 20, 1952, Serial No. 22,383

Term of patent 7 years

(Cl. D44—10)

To all whom it may concern:

Be it known that I, Robert B. Karoff, a citizen of the United States and a resident of New York city, county and State of New York, have invented a new, original, and ornamental Design for a Collapsible Tray, of which the following is a specification, reference being had to the accompanying drawing, forming a part thereof, in which:

Fig. 1 is a perspective view of the collapsible tray showing my new design, in which the tray leaves are shown in nested position; and

Fig. 2 is a perspective view of the same showing the tray leaves in radially spread position.

I claim:

The ornamental design for a collapsible tray, as shown.

ROBERT B. KAROFF.
